[57] **CLAIM**

The ornamental design for a combined gem and coil spring support for toes, as shown and described.

DESCRIPTION

FIG. 1 is a perspective top view of a combined gem and coil spring support for toes, showing my new design;

FIG. 2 is a top plan view thereof;

FIG. 3 is a bottom plan view thereof;

FIG. 4 is a front elevational view thereof, the right side, the left side and the rear elevational views being all identical therewith;

FIG. 5 is a longitudinal cross sectional view thereof, taking along lines 5—5 of FIG. 2; and,

FIG. 6 is a top plan view in position of use thereof, the toes and the portion of a sandal being shown in broken lines for illustrative purposes.
